HAT

Jesse B. Hawley, Geneva, Ill.

Application February 4, 1935, Serial No. 4,866

2 Claims. (Cl. 2—192)

The present invention relates to hats and more particularly to hats made of fibrous material.

Among the objects of the invention is to provide a novel hat composed of a novel composition and 5 the novel composition thereof.

Another object of the invention is to provide a novel hat which will be light in weight, which has excellent heat transfer insulating properties, which will not absorb and hold fluids and thus 10 will be fluid proof, which is impervious to fluids, which may be easily cleaned by the usual cleaning agents without any injurious effects to the hat, which is stiff, tough and durable, which may be colored and decorated as desired, which may 15 have coverings of any desired material, which will maintain its shape or form, and which may have the appearance of a hat made of other material.

A further object of the invention is to provide 20 a novel hat which may be produced quickly with simple operations at small expense and cost and on a large scale or in a large capacity of production without the necessity of making the hats of different sizes to fit the different sizes of heads 25 thus eliminating the need for different equipment, machinery and apparatus for different sizes of hats, which will be accurately and uniformly made, which in the manufacturing thereof may be made in any desired shape or form, 30 which will be compressed or compacted as desired, which will have sharp, well defined and distinct features, ornate or otherwise, which will be practically fireproof, which will have any surface finish desired and any color or combination 35 of colors as desired, and which will have an attractive appearance.

The invention also comprehends the producing 40 of a novel hat composed of fibrous material initially deposited, accreted, interlaced and integrated so as to form a seamless integral and stiff hat in the final desired shape, form or contour and character, free of internal stresses tending 45 to change its form, shape or contour as initially produced, thus avoiding warping, distortions and the like. The hat of the present invention is 50 made or composed initially in its final and intended form of fibrous material deposited, accreted, interlaced, molded and integrated preferably upon a contoured porous former so that 55 the member so produced is seamless, of the desired thickness and compactness or density, light in weight, stiff, tough and durable, and without any deforming stresses and strains. There is no tendency for it to change to any other shape or contour or even to become distorted to any de-

gree, because it is not deformed from any other shape or contour, and hence it remains normally of the shape it initially received when molded or accreted etc. Should anything tend to change its shape, it will restore itself to its original shape 5 or state, thus making for permanency of form and condition.

Another advantage of making the hat by accreting fibrous material upon a contoured porous former is that any desired shape, contour and 10 design feature may be obtained which would be impossible to effect by the deformation of a sheet of material, the final desired form being produced by the present invention initially when the fibres 15 are accreted, interlaced and integrated.

Other objects, advantages, capabilities, features and the like are comprehended by the invention as will later appear and as are inherently possessed by the invention.

Referring to the drawings;

Fig. 1 is a vertical sectional view through a 20 means for forming the hat from fibrous material;

Fig. 2 is a similar view with parts broken away 25 of a male drying die;

Fig. 3 is a view similar to Fig. 2 of the male 30 drying die with a female drying die;

Fig. 4 is a vertical sectional view of a heat transfer die or die means which may be used in lieu of dies shown in Figs. 2 and 3;

Fig. 5 is a fragmentary top plan view of a 35 part of the die means shown in Fig. 4;

Fig. 6 is a horizontal sectional view taken in planes represented by line 6—6 in Fig. 4 of the 40 drawings;

Fig. 7 is a vertical sectional view of a hat blank 45 made in accordance with the invention;

Fig. 8 is a similar view showing a hat having 50 coatings or coverings;

Fig. 9 is a fragmentary sectional view of a male 40 die and a hat blank showing the application of 55 coverings or coatings on the blank;

Fig. 10 is a view in elevation of a hat constructed in accordance with the invention;

Fig. 11 is a bottom plan view of the same and 45 showing the application of a sweat band and a chin strap; and,

Fig. 12 is a fragmentary sectional view of the 50 means for connecting the sweat band to the hat.

Referring more in detail to the drawings, the 55 hat is produced from fibrous material, such as pulp or the like, and may include any other fibrous material such as wool, cotton, linen, silk, jute, hemp, asbestos, kapok and similar fibrous material, the term pulp being herein used generi-

cally to include any or any combination of the various fibres that may be used. For the purpose of carrying out the invention the fibrous material is placed with water in a beater or beater 5 engine to beat the fibres and to disintegrate and disperse them in the water, and also to shorten and hydrate the fibres to the desired point or extent.

The mixture or batch as it is usually called is 10 then treated with suitable substances to "proof" the fibres. This may be effected in any of several ways. As for example, while continuing the beating of the material in the beater engine, water proofing wax or wax emulsion may be added 15 to the mixture, as in the proportion of about 0.25 to 8% of the weight of the dry material first placed in the beater. The beating and stirring may be continued for a sufficient period of time, such as from about 10 to 15 minutes until the wax 20 or wax emulsion has been thoroughly dispersed and mixed or incorporated with the fibres, after which powdered alum or a solution of alum may be added in a quantity sufficient to set the wax on or in the fibres. This wax or wax emulsion 25 has the property of softening, and water and moisture proofing the fibres, as also smoothing the surfaces of the fibres. The beating and stirring may continue until the setting has been effected, and then the material, termed "stock", 30 may be stored in a suitable tank or vat for use when molding or accreting on the porous former or die.

As other examples, in lieu of wax or wax emulsion, paper maker's rosin in an amount of about 35 1 to 5% of the weight of the dry material first placed in the beater may be used, or latex, or powdered or emulsified asphalt, and the like may be used, each of which may also be set with alum as above described in connection with wax. The 40 rosin has the property of stiffening, and water and moisture proofing the fibres. The latex toughens and renders the fibres resilient or resistant to deformation and the like. The asphalt is used to give the fibres water and moisture 45 proofing characteristics as also for stiffening the fibres.

As further examples, proofing may likewise, by a like or similar process, be effected with starch, glue, casein, or silicate of soda, and the like, in 50 which case setting with alum is not necessary as in the cases referred to above. The starch stiffens and smooths the fibres. The glue, casein and the silicate of soda stiffens the fibres. The glue is particularly useful in connection with wax 55 to counteract the softening effect the wax has on the fibres.

The fibrous material preferably used is that of pulp or pulp mixed with other fibres as desired. The pulp or pulp component may be of 60 kraft fibres such as southern kraft fibres, sulphite pulp, or rope pulp, wherein the material is stiff and will produce a comparatively stiff hat. When using softer fibres such as soda pulp, the material is softer and produces a less stiff hat. 65 The sulphite pulp reduces the shrinkage of the kraft pulp and adds strength when used with the soda pulp, and hence it is preferable to use sulphite pulp especially the Mitscherlich pulp, with either the kraft or soda pulp. The un- 70 bleached fibres are stronger than the bleached fibres, while the Mitscherlich sulphite pulp is stronger than the common type of pulp fibres. Preferably the kraft and sulphite pulp, both common and the Mitscherlich type, are used. 75 By mixing the stiffer with the softer materials

with or without the other fibrous material mentioned above, any desired degree of stiffness or softness may be had.

The means selected to illustrate the invention comprises a molding or forming die in the form of a contoured plate 1 provided with a plurality of openings or apertures 2, the lower rim 3 of the plate being seated upon a table or platen 4 having an apertured hub 5 in which is secured the upper end of a duct 6 leading to a suitable 10 source of suction or pressure (not shown). The platen 4 is adapted by suitable means (not shown) to be lowered into and raised out of the bath 7 in a vat or tank 8. The plate 1 and the platen 4 enclose a chamber 9 in which is normally created a suction for the drawing of the water of the bath through the holes 2. The bath 7 consists of water and fibrous material which is maintained in dispersed suspension in 15 the water by suitable agitation of the bath by 20 any desired means (not shown).

The upper and outer surface of the plate 1 is shaped or contoured to conform with the shape or form of hat to be molded thereon. Upon this contoured surface is a reticulated sheet or screen 25 10 of fine mesh conforming in shape or contour to the surface contour of the plate 1.

In operation, with the device in the position shown in Fig. 1, a suction is created in the chamber 9, and the platen 4 with the plate 1 and screen 10 are lowered and submerged in the bath 7. The suction draws the water through the interstices of the screen 10 and the holes 2 to be delivered to the duct 6, causing a deposit, accretion, interlacing and integration of the fibres 35 in the form of a contoured layer or stratum 11 on the screen 10, the thickness and compactness or density of this stratum depending upon the time of immersion, the magnitude of the suction, the nature of the fibres, and the percentage of 40 fibres in the bath. In some cases setting up a vibration in the mold will also have some effect, particularly in the interlacing of the fibres.

When the desired layer or stratum is accreted, interlaced and integrated, the platen 4 and the 45 mold die 1—10 with the fibrous stratum thereon are raised out of the bath. The suction during emergence is continued to prevent the washing away of some of the fibrous material, and also, after emergence, to draw air through the fibrous 50 blank or stratum for removing surplus water, that is, as a preliminary drying of the same. If desired warm or heated air or the like may be thus drawn through the blank to dry the blank but it is preferable to dry the blank in a manner hereinafter disclosed.

To assist in expelling the surplus water in the blank, a female die 12 shown in dotted lines in Fig. 1 may be applied to the blank with pressure to squeeze out some of the water as also to partly 60 compress or compact the blank, the suction in the chamber 9 continuing to draw out this water and discharge it through the duct 6.

The female die 12 comprises a contoured wall or plate 13 conforming to the shape or contour 65 of the blank, and having holes or apertures 14 for the passage of air. At the base is provided a base flange 15 upon which seats the lower edge portion 16 of the housing or casing 17 of the female die, this casing comprising walls 18 70 and a top 19, thus enclosing a chamber 20 about the wall 13. At a suitable low point is connected a pipe or duct 21 for the discharge of any water that may be drawn through the apertures 14 under the influence of the vacuum created in the 75

chamber 20 at the time when the wet blank 11 is compressed between the die walls 1 and 13. The die 12 serves as a transfer means for the blank 11. After the blank 11 has been compressed, the vacuum in chamber 9 is discontinued and a pressure is effected therein while a suction is created in chamber 20 of the female die. The die 12 is then lifted and the blank 11 will be lifted with it, the blank adhering to the wall 13 of the die 12. The die 12 with the blank 11 clinging to it are then brought over a hot male die 22 having a contoured wall or plate 23 provided with a plurality of holes or apertures 24. The lower portion of the wall 23 has a rim 25 which seats upon a table or platen 26 having an apertured hub 27 in which is connected a pipe or duct 28 leading to a suitable source of suction or pressure (not shown). The wall 23 and platen 26 thus enclose a chamber 29. The die 12 and blank 11 are moved down so as to set the blank 11 on the contoured wall 23 as shown in Fig. 2, the die 12 applying the necessary pressure to compress and compact the fibrous material of the blank 11, and the vacuum therein being changed to a pressure so as to relieve the blank from the die 12 and to cause it to adhere to the die 22, after which the die 12 is removed. The heat of the die wall 23 converts the moisture or water remaining in the blank to steam, vapor and the like, which are drawn through the apertures 24 by reason of the vacuum in chamber 29 and are discharged through the duct 28. If desired heated or hot air, gas, or other medium may be drawn through the blank and the holes 24 to effect a drying of the blank, but it is preferable to apply a hot female die 30 comprising an imperforate contoured wall or plate 31 the lower edge portion of which has a flange 32 upon which the lower edge portion 33 of the housing or casing 34 seats. The casing 34 may be octagonal in shape and comprises end walls 35 and 36 (see Fig. 6), side walls 37 and 38, angle walls 39, 40, 41 and 42 provided with openings 43, 44, 46, and 45 for the projection of flames from burners 47, 48, 50 and 49 into the chamber 51, and a top wall 52. Besides applying heat the wall 31 also applies pressure to compress and compact the fibrous material of the blank 11 as also to give the blank the desired finished definition of contour. The steam, vapors, moisture, and the like are drawn through the holes 24 and discharged through the duct 28.

If desired, and preferably, the drying and compressing may be effected on the heat transfer die shown in Figs. 4, 5 and 6 wherein is shown a male die comprising a wall or plate 53 having at its lower edge a flange 54 seated upon a table or platen 55, thus enclosing a chamber 56 for containing a heat transfer medium. At the top the wall 53 has an opening 53a with which communicates a duct 57 preferably formed integral at its upper end to the plate 53 and having its lower open end 58 located in an aperture provided in the platen 55 (Fig. 4). The platen 55 is clamped to a platen 59 which has an opening 60 in line with the opening in platen 55 in which the duct portion 58 is located, and in which is connected an end of a duct 61 leading to a suitable source of suction (not shown). Both platens 55 and 59 are provided with openings 62 and 63 for projection therethrough of flames from burners 64 into the chamber 56.

In the upper or outer contoured surface of the wall 53 are provided a plurality of channels or grooves 65, 66 and 67 extending more or less radially and of which channels 65 lead to and com-

municate with the opening 53a, there being also cross channels 68, 69, 70 and 71 more or less circular or oval shaped for establishing communications between and among the channels 65, 66 and 67 whereby steam, vapors etc. may be led to the opening 53a and duct 57.

Upon the wall 53 is located a contoured die wall 72 having a plurality of holes or apertures 73, and being provided at its lower edge portion with a flange 74 seated upon the flange 54 of the wall 10 53. At the top the wall 12 has a boss 75 to conform with the top knot feature in the hat blank to be later more fully described.

The upper and outer contoured surface of the wall 72 is covered by a thin fine mesh reticulated member or screen 76 having the same contour as the wall 72, and having a base flange 77 seated upon the flange 74 of the wall 12 and an upper boss 78 conforming to the boss 75.

The hat blank 11 reposes on this screen having been transferred from the molding die shown in Fig. 1 by the transfer die 19 and placed upon the screen 76 by changing the vacuum in the chamber 20 of the transfer die 19 to a pressure, after which the transfer die is removed, and the female die 30 is brought in place to compress the blank 11.

The wall 31 of the female die 30 is contoured to the desired shape to be given to the hat blank, and has its base flange 32 above or over the flange 30 77 of the screen 76 and has at the top a boss 79. It will be noted that the die walls 72 and 31 as also the screen 76 have contoured design features, such as bosses 75, 79 and 78 to form a boss 80 in the blank 11 in representation of a top knot 35 on the hat (Figs. 7, 8, 10 and 11), also ribs running radially over the crown part to form ribs 81 in the hat blank in representation of seams or the like on the hat crown (Figs. 7, 8, 10 and 11), and also ridges 82, 83 and 84 to form ridges 85 in 40 the hat blank in representation of folds or pleats 85 on the hat (Figs. 7, 8, 10 and 11).

While the female die compresses the blank 11, hot products of combustion are projected through the burner holes into the chambers 56 and 51 45 so as to heat the walls 53 and 31 and to supply heat to the wall 72 and to the blank 11. A suction is effective in the duct 57 whereby the steam, vapors, and moisture formed in the material of the blank will be drawn off by way of the reticulations of the screen 76, the holes 73 in the wall 72, the channels 65-71 in the surface of the wall 53, and thence to the opening 53a and through the ducts 57 and 61. The blank is thus dried and set with the desired finish definition 55 as impressed by the particular surface contour of the die walls and the screen 76. The female die 30 may then be removed and the blank taken off of the screen 76. If desired a transfer die similar to that shown in Fig. 1 with a suction in 60 its chamber may be used to remove the blank from the screen 76, after which a pressure in the chamber of the transfer die will suffice to blow off the blank.

The hat blank or carcass shown in Fig. 7 is 65 therefore substantially stiff, strong, tough, and water and moisture proof, the fibres from which it is composed having been treated in the beater with the "proofing" substances mentioned above. The material of the blank is particularly of the 70 kind which, when a part of the hat is displaced or strained, will either be readily restored to its original form without any injury to the hat, or restore itself to its original shape when the straining stress is removed, a characteristic which 75

is not present in articles accreted in the usual way from the usual fibres, the "proofing" substances and the mode of "proofing" giving the material, in this invention, the peculiarly new and beneficial properties and characteristics mentioned above. The moisture and water proofing quality is such as to make it unnecessary to coat the hat with a coating or covering of water and moisture proofing substance, but in the present invention it is preferable to apply a coating either on the outside or inside surface or both to form a covering or skin which will seal off the interstitial spaces or cells in the fibrous body of the blank particularly for effecting insulation against heat transfer, although incidentally the coating will also add to the water and moisture proofing property or characteristic of the hat body.

After the blank, as shown in Fig. 7, has been thus dried and set, it is preferable to coat, as by brushing, the outer surface of the blank with a "size" so as to form the coating or skin referred to above. If desired, particularly in the case of where the inside of the hat is to have no cloth covering or to have only a cloth liner on the inside of the brim, a like coating may be applied on the inside surface of the hat. In the case where both the inside and outside surfaces of the hat are to be wholly cloth covered, it is preferable to omit the inner coating of the size. For the purpose of illustration the coatings are designated by the reference characters 86 and 87 in Fig. 8 of the drawings.

The "size" preferably used is that known as nitrocellulose cotton which is dissolved in lacquer solvents, and is preferably pigmented with any of the various enamel pigments of the color the hat is to have, or any suitable dye may be incorporated for the same purpose. If desired any other similar "size" may be used such as that made from acetate cotton. Even latex or rubber cement and the like may be used. The "size" does not penetrate the fibrous mass but simply forms a sealing coating or skin on the surface of the blank. The coating or coatings, as the case may be, also increase the water proofing properties or characteristics of the hat material. These coatings form sealing coverings or skins which hermetically seal the interstitial spaces or cells within the fibrous material of the blank, so that they will act as heat insulating means.

After the coatings are dry, either the outside or both the outside and the inside may then be coated with a coating 88 and/or 88^a of a thermoplastic substance preferably of a resin base, or the like, the thermoplastic being preferably applied by spraying in liquid form and having a volatile solvent. When applying the coating 88 on the outside, and before applying coating 88^a on the inside, it is preferably done by first placing the hat blank 11 on a rubber or like male die 89 fixed to a platen 90 (Fig. 9) having a support 91. After the volatile solvent has evaporated and the thermoplastic substance has dried, a hot female die with the proper contoured wall is pressed against the coated blank with requisite pressure. The heat of the female die causes the thermoplastic substance to fuse and be displaced to conform to the definition of the contoured surface of the die wall. Then the die is allowed to cool and the thermoplastic substance sets and congeals to form a tough durable covering for the hat, after which the dies are removed and the hat is ready to receive the sweat

band and the chin strap. The inner coating 88^a is omitted at this instant to prevent it adhering to the die. If the thermoplastic substance is to be applied on the inner surface of the blank, the same procedure is used, but the female die in which the hat blank is placed with the inside of the hat blank uppermost is of metal, and after applying and drying the thermoplastic substance, a hot male die is applied to fuse the thermoplastic substance which is set after cooling, as in the previous case. The same result may be effected by simply coating both the inside and the outside surfaces of the carcass with the thermoplastic substance, and after drying, placing the coated carcass between male and female hot dies, then when the thermoplastic substance has sufficiently fused the dies are removed and the thermoplastic substance sets to form a stiff tough coating.

The thermoplastic substance referred to is in the class of synthetic resinous compounds known as the vinyl resins of the polymerization group and more particularly those which are permanently thermoplastic; characterized by the bond group or radical —CH:CH₂, and which are insoluble in most all known solvents, particularly the hydrocarbon solvents, except the solvents of the ester type or the higher ketones, such as hexone and butyrene. In other words, the substance used in this invention is chemically inert to the extent indicated above and hence is impervious to and proof against moisture, water, acids, alkalies, alcohols, oils, greases, fats, and the like. In its normally pure state it is odorless, tasteless, colorless, and transparent. It is also non-inflammable. It may be given any color or made translucent or opaque as desired by the incorporating or mixing therewith of dyes, pigments, fillers, or the like. It is also tough, durable and resilient. It also has a very strong bonding or adhesive property. It may be applied either in liquid or solid form or both. When using this substance in liquid form, acetone preferably is used as the solvent but it is to be understood other solvents as mentioned above may be used without affecting the idea of invention herein disclosed.

In the present invention the thermoplastic substance is preferably applied to the surface of the coated hat blank by spraying in liquid form although it might be applied with a brush. As the volatile solvent evaporates the liquid thickens and even becomes tacky. Air drying may be used but if desired the coating may be dried more quickly in heated air or the like. It is preferable to air dry first to obtain a removal of the major portion of the volatile solvents, and then force dry in heated air, to remove the residual volatiles.

As indicated above, the die is applied with pressure. It is heated to the necessary temperature to fuse and melt the thermoplastic substance so that it will be sufficiently plastic or fluidal to be easily displaced and to flow under the influence of heat and pressure of the die. The die is then either removed or cooled or permitted to cool so that the thermoplastic substance will congeal or solidify and set. This substance acts as a stiffener or reinforcer for the body of the hat, also as a protecting and preserving means preventing the access of moisture and other deteriorating media, etc. to the material of the hat, and also in some cases as an adorning or embellishing means to give the hat an appearance of elegance and the like.

If desired the hat blank may have cloth or like coverings on either or both the outer and inner

surfaces of the hat. In that case the cloth is stretched over the surface of the blank by contoured hot dies which fuse the thermoplastic substance which permeates the cloth and on cooling causes the cloth to adhere firmly and permanently to the hat blank. This is more fully disclosed in the co-pending application of Edward C. Sloan and Gustave A. Sporre identified as Serial No. 4,862, filed February 4, 1935 and assigned to me.

10 In Figs. 11 and 12 is shown a method of attaching the sweat band 92 and the chin strap 93. In the form shown the band 92 is connected at spaced points to the upper ends of connecting members 94 preferably of resilient material, each 15 member 94 comprising a lower end portion 95 suitably apertured to receive a shank 96 of a snap lug 97 of the glove snap type of connection, the shank 96 having flanges 98 and 99 on each side of the end portion 95 to bear against it with 20 sufficient friction to hold the parts in adjusted position as explained later. The lug 97 fits into a snap socket 100 which is set in a hole formed in the hat juncture between the crown and the brim of the hat as shown. The socket 100 has 25 an outer hollow flange or head 101 of sufficient size to afford substantial bearing against the outside surface of the hat, and an inner flange 102 bearing against the inner surface of the hat juncture mentioned. The member 94 at its upper end 30 has a bend 103 and a depending end portion 104 apertured to receive a hollow rivet or eyelet 105 extending through the sweat band 92 as shown.

The sweat band preferably is made of suitable material so that it will normally hold a general 35 oval shape as shown in Fig. 11, and yet be capable of being fitted comfortably to the head. The band 92 has spaced end portions 106 and 107 having eyelets 108 and 109 through which is threaded a tape or cord 110 having free ends 111 and 112 40 adapted to be tied into a knot 113 at such a point as to shorten or lengthen the laps of the tape between the band ends 106 and 107 to respectively decrease or increase the size of the band in accordance with the size of the head of 45 the wearer.

The connecting members or elements 94 are so connected as to be angularly adjustable about the axes of the snap lugs 97 and the eyelets 105, so that as the sweat band is decreased or increased in size the connecting members or element 94 swing in compensation with such change in size of the band. The sweat band is spaced from the crown of the hat to afford an air circulation space between the band and the hat 55 crown. The members 94 are also resilient so that as the sweat band is fitted to the head of the wearer the members 94 flex in compensation thereto while at the same time resiliently but comfortably pressing the band against the head.

60 The end portions 114 and 115 of the chin strap 93 are connected to the hat by way of snap means 116 and 117 of the same type and con-

struction shown in Fig. 12 so that the chin strap may be readily detached or attached as desired.

The hats are all made of a size, and the sweat band and chin strap nearest the size of the head of the wearer are readily attached, and the tape 5 or cord 110 is so tied as to effect the exact size in the sweat band for the particular head to wear the hat.

When it is desired to clean the hat or if the hat is to be used by another wearer, the hat band 10 and the chin strap are easily and quickly detached, after which the sweat band and the chin strap, or a new sweat band and chin strap are as easily and quickly attached in place.

Because the hat is covered with a thermoplastic 15 substance not affected by the usual cleaning agents, the hat may be readily cleaned thereby.

A hat constructed and composed in accordance with the present invention, is light in weight, 20 very durable, stiff, water and moisture proof, impervious to liquids, has excellent heat transfer insulating properties, will not become deformed, has a very attractive appearance, and may be of any desired color.

While I have herein disclosed an embodiment 25 of the invention, it is to be understood that the invention is not limited thereto but comprehends other constructions, details, arrangements of parts, features, and the like without departing from the spirit of the invention.

Having thus disclosed the invention, I claim:

1. A hat comprising a body composed of compressed pulp material the fibers of which have been initially so accreted and compressed as to form a relatively thin substantially rigid integral 35 unit into the final desired form and provided with interstitial spaces among the fibers to act as heat transfer insulating cells, and a waterproof covering on at least one surface of said body for sealing the interstitial spaces at said surface and 40 contributing to the stiffness of said body.

2. A process of making relatively thin substantially rigid hats each having a body composed of fibrous material, comprising the steps of treating the individual fibers while suspended 45 and dispersed in a fluid bath with a proofing substance to make the fibers proof against absorption of moisture when composed in said fibrous material, depositing, accreting, and integrating said treated fibers from said fluid bath 50 upon a contoured porous former under a differential of pressures on the opposite sides of said porous former to produce a blank of given thickness of fibrous material and with interstitial spaces among the fibers of said material of said 55 blank, drying and finishing said blank to give it the desired definition of contour, and adhering a covering to a surface of said dried and finished blank to seal the interstitial spaces at said surface against the passage of heat and air.

JESSE B. HAWLEY.
